UNITED STATES PATENT OFFICE.

HOWELL D. PRATT, OF PHILADELPHIA, PENNSYLVANIA, ASSIGNOR TO LINK-BELT COMPANY, OF CHICAGO, ILLINOIS, A CORPORATION OF ILLINOIS.

BOX-CAR LOADER.

1,346,680.

Specification of Letters Patent. Patented July 13, 1920.

Application filed June 12, 1918. Serial No. 239,522.

To all whom it may concern:

Be it known that I, HOWELL D. PRATT, a citizen of the United States, residing in Philadelphia, Pennsylvania, have invented 5 certain Improvements in Box-Car Loaders, of which the following is a specification.

My invention relates to certain improvements in box car loaders of the type which will receive material at the ground level and 10 will deliver it into a car, or other carrier.

The object of my invention is to construct a machine of this type so that material can be delivered into a box car, or other car having a closed top, and distributed throughout the length of the car. The invention is 15 preferably applied to a bucket elevator in which the buckets take the material from the ground and deliver it into the car.

In the accompanying drawings:

20 Figure 1 is a side view of my improved car loader;

Fig. 2 is an end view looking in the direction of the arrow 2, Fig. 1;

Fig. 3 is a plan view of a portion of the 25 loader; and

Fig. 4 is a view of a modification.

Referring to the drawings, 1 is a platform supporting the structure. This platform is mounted on an axle 2 having wheels 3, the 30 axle being near the center of the platform.

4 is an axle mounted on a pivot 5 provided with wheels 6 of much smaller diameter than the wheels 3. By this means the structure can be readily moved from one point to another. 7 is a bucket elevator, the chains 8 of which pass around the upper sprocket wheel 9 and the lower sprocket wheel 10. The upper sprocket wheel 9 is the driven wheel in the present instance and is driven

40 by a chain 11, which passes around a sprocket wheel 12 on a driven shaft 13, which has a sprocket wheel 14 at the opposite end around which passes a chain 15 from a sprocket wheel 16 on a shaft 17, which is

45 geared to the armature shaft 18 of the motor 19 contained within the housing 20 supported by the platform 1. The buckets 21 of the elevator are located a given distance apart and are arranged to receive material directly from a pile and carry it to the upper 50 end of the structure. This elevator is supported on a suitable frame 22, the character of the frame depending upon the size and weight of the parts.

55 I preferably locate a dust collector 23

under the return run of the elevator so as to carry the dust back to the ground. In some instances, where the material is to be discharged from a wagon directly onto the conveyer a boot 24, shown in Fig. 4, may be 60 used to receive the material. At the upper end of the structure is a discharge chute 25 onto which the material is discharged from the buckets and below this chute is a hopper 26 carried by a frame 27 pivoted at 28 to a 65 bracket 29 secured to the main structure at such a height that it can extend into the door opening in a box car. The pivot 28 is a sufficient distance from the main frame so that an endless belt conveyer 30 can be 70 carried by the frame 27 and will extend into the car, assuming different positions therein so that it can load the car.

The belt 31 of the conveyer 30 passes around wheels 32 and 33 mounted on a frame 75 27, of any suitable construction, and mounted on this frame is a small electric motor 35, in the present instance geared to a shaft 36 which, in turn, drives the shaft 37 through a chain and on the shaft 37 is mounted the 80 wheel 32. The belt 31 may have a series of cleats or cross bars 38, if found desirable. A chain 39 is attached to the frame and to the chute and supports it at any angle desired. The length of the chain can be altered by a turnbuckle 40.

By having an independent motor, the speed of the motor can be varied so that the material can be discharged from the end of the belt at a greater or less speed, and by 90 controlling the motor the position of the material in the car can be varied. By turning the conveyer on its pivot, the material can be discharged at any point in the car.

While I have described my invention as 95 particularly adapted for loading cars, it will be understood that it can be used for loading stationary bins, or carriers of any description.

It will be seen by the above description 100 that I am enabled to make a comparatively cheap car loading device which will continuously handle material in comparatively large amounts and which can be operated by one man and can be readily shifted from place 105 to place.

I claim:

1. In a car loader, the combination of a 110 readily portable frame having a horizontal relatively short wheel base and a vertical

portion of substantial height; a bucket elevator mounted at an incline on one side of the frame, said frame having a lateral extension from the opposite side at a point intermediate of its top and bottom; a motor for driving the elevator; a pivoted belt conveyer having a frame pivotally mounted at one end of said lateral extension so that the conveyer is capable of swinging about its pivot either to the right or left of the loader, said conveyer adapted to receive material from the bucket elevator; and an independent motor for driving the belt conveyer so that the speed thereof can be varied to cause material to be discharged at different distances from the loader.

2. In a car loader, the combination of a readily portable frame having substantial height and a relatively short wheel base, an

inclined bucket elevator mounted on one side 20 of the frame, said frame having a bracket extending horizontally from its opposite side at a point between the top and bottom of the frame, and a flight conveyer having one end pivotally mounted on said bracket 25 so that the conveyer may be swung through an arc of 180 degrees to discharge material either to the right or left of the loader; an independent motor for driving the conveyer at variable speed to permit material to be 30 delivered at different distances from the loader, a chute into which the upper end of the bucket end of the elevator discharges; and a hopper on the flight conveyer into which the chute delivers.

35 In witness whereof I affix my signature.

HOWELL D. PRATT.
